UNITED STATES PATENT OFFICE.

HARRY E. CROSS, OF ROCKTON, ILLINOIS.

DESIGN FOR AN AUTOMOBILE-BODY.

55,845.

Specification for Design.

Patented July 20, 1920.

Application filed November 29, 1919. Serial No. 341,542. Term of patent 3½ years.

To all whom it may concern:

Be it known that I, HARRY E. CROSS, a citizen of the United States, residing at Rockton, in the county of Winnebago and State of Illinois, have invented a new, original, and ornamental Design for an Automobile-Body, of which the following is a specification, reference being had to the accompanying drawing, forming part thereof.

In the drawing,—

Figure 1 is a plan view of an automobile body, showing my new design;
Fig. 2, a side view thereof; and
Figs. 3 and 4, rear and front views respectively, of the body.

I claim:

The ornamental design for an automobile body, as shown.

HARRY E. CROSS.
